(57) **CLAIM**

The ornamental design for a security camera, as shown and described.

DESCRIPTION

FIG. 1 is a front, right, top perspective view of a security camera showing my new design;

FIG. 2 is a rear, left, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right, top perspective view of the security camera in an alternate configuration.

The broken lines are for the purposes of illustrating portions of the security camera and form no part of the claimed design.
